CLIP FOR ATTACHING MUDGUARD STAYS TO MUDGUARDS

Claude Arden Buckley, Birmingham, England, assignor of one-half to The Speedwell Gear Case Company Limited, Birmingham, England, a British company

Filed Oct. 18, 1962, Ser. No. 72,179

Term of patent 7 years

(Cl. D17—3)

Fig. 1.

Fig. 2.

Fig. 3.

Fig. 4.

FIGURE 1 is a perspective view of a clip for attaching mudguard stays to mudguards showing my new design,

FIGURE 4 is a side elevational view.

I claim:

The ornamental design for a clip for attaching mud-guard stays to mudguards, substantially as shown.
